WASHBASIN

Filed Nov. 25, 1929

Inventor
Ferdinand G. Schindoski
By Fred Gerlach Atty.

UNITED STATES PATENT OFFICE

FERDENAND G. SCHINDOSKI, OF CHICAGO, ILLINOIS, ASSIGNOR OF ONE-FOURTH TO
JAMES E. MOLLOY, OF NORWOOD, OHIO

WASHBASIN

Application filed November 25, 1929. Serial No. 409,484.

The present invention relates generally to washbasins. More particularly the invention relates to that type of washbasin which is formed of a one piece casting and comprises a bowl and a top plate which is provided with supporting legs and faucets for filling the bowl and embodies a central opening through which access may be had to the bowl.

Heretofore it has been customary in the manufacture of washbasins of the aforementioned type to form the top plate so that the front portion thereof terminates in close proximity to the front of the bowl and is straight, rounded or slightly indented in the central part thereof. In practice it has been found that when the top plate is formed in this manner the user of the basin often soils his or her clothes and wets the subjacent floor by reason of the fact that the forearms, during washing of the hands and face, are positioned outwardly of the top plate and water is permitted to drip from the user's elbows towards the floor.

The primary object of the invention is to provide a washbasin of the character under consideration in which the front portion of the top plate is provided with a pair of laterally spaced extensions which are shaped to receive therebetween the waist part of the user of the basin and are of such length and design that they underlie the user's forearms and elbows, during use of the bowl for washing of the hands or face, and operate to catch any and all drippings from the elbows and to drain the same into the bowl.

Another object of the invention is to provide a washbasin which is generally of new and improved construction, may be manufactured at a comparatively low cost, and has certain inherent advantages over previously designed basin of a similar character or type.

Other objects of the invention and the various advantages and characteristics of the present basin construction will be apparent to those skilled in the art from a consideration of the following detailed description.

The invention consists in the several novel features hereinafter set forth and more particularly defined by the claim at the conclusion hereof.

In the drawing which accompanies and forms a part of this specification or disclosure and in which like numerals of reference denote corresponding parts throughout the several views:

Figure 1 is a vertical longitudinal sectional view of a washbasin embodying the invention, disclosing in detail the construction and arrangement of the extensions and illustrating the manner in which such extensions are adapted to underlie the elbows and forearms of the user of the bowl so as to catch the elbow-drippings; and

Figure 2 is a plan view of the basin.

The washbasin which forms the subject matter of the present invention is formed of a one piece casting and comprises a bowl 5 and a slab or top plate 6. The latter is rectangular in conformation, embodies at the sides and back thereof a vertically extending flange 7, and has formed therein a central opening 8. The bowl 5 underlies the central portion of the top plate and is joined to the part of said plate that defines the opening 8. Faucets 9 for supplying water to the bowl are mounted on the back part of the top plate and are connected to supply pipes 10. A drain or outlet orifice 11 is formed in the bottom of the bowl. This orifice is connected to discharge into a pipe 12 of the gooseneck type, and is adapted to be closed by a stopper or valve so that the bowl may be filled with water from the faucets 9. The vertical flange 7 projects slightly above the top plate 6 so as to form a bead or rim for preventing any water that is splashed onto the top plate from flowing over the sides or back of the basin. The top plate slopes inwardly and downwardly from the bead-forming flange 7 in order to cause the splashed water to drain back into the bowl.

In addition to the bowl and top plate, the washbasin comprises a pair of laterally spaced extensions 13. These extensions are formed integrally with the top plate 6 and project forwardly from the front portion of the basin. The inner or oppositely facing side parts of the extensions are joined together at the inner parts thereof and are curved so as to be concave and to form together a semi-

circular pocket 14 which is positioned directly in front of and in close proximity to the bowl and is adapted to receive and conform substantially to the waist region or part of the user of the basin. The outer side parts and the outer ends of the extensions are adapted to underlie the user's forearms and elbows, respectively, so as to catch all drippings that occur during washing of the hands or face and prevent such dripping from dropping downwardly onto the clothes of the user or the floor. The extensions are preferably formed so that the outer side parts thereof are flush with the sides of the top plate. A flange 15 is formed integrally with the marginal parts of the extensions and is in the nature of a continuation of the flange 7. The extensions slope downwardly towards the bowl so that the dripping drain onto the top plate and through the opening 8. The outer ends of the extensions are rounded so as to present no sharp corners and conform more or less to the elbows.

In washing, the user of the basin will stand directly in front of the bowl with his or her waist region in the pocket 14. In this position the user may wash the hands or face without the remotest possibility of wetting the subjacent floor or soiling the clothes for the reason that any drippings from the elbows or forearms are caught by the extensions and returned to the bowl 5.

The washbasin herein disclosed may be readily installed, takes up but a comparatively small amount of space, and may be manufactured at a comparatively low cost. It is to be distinguished from basins having a slight notch or recess in the front thereof for reception of the user's neck in shampooing, by reason of the fact that extensions 13 are of such length and character that they serve to underlie the elbows and forearms and form a semi-circular pocket into which the user's waist is adapted to fit.

The invention is not to be restricted to the details set forth since these may be modified within the scope of the appended claim without departing from the spirit or scope of the invention.

Having thus described the invention, what I claim as new and desire to secure by Letters Patent, is:

As a new article of manufacture, a wash basin comprising a rectangular top plate having a substantially circular opening in the front portion thereof, a bowl of normal size connected to the top plate and positioned beneath the opening, and a pair of laterally spaced, marginally flanged, elongated extensions connected to and projecting forwardly from the front corner portions of the top plate and having the oppositely facing side parts thereof shaped so as to form therebetween and directly in front of and near the bowl opening a comparatively large semi-

circular pocket for receiving and completely surrounding the front and side portions of the waist of the user of the basin, said extensions being approximately half the depth of the top plate and of such area and design that during the use of the bowl they underlie completely the user's elbows as well as forearms in order to catch all drippings therefrom, and being inclined towards the plate so as to drain such drippings into the bowl.

Signed at Chicago, Illinois, this 21st day of November, 1929.

FERDENAND G. SCHINDOSKI.
